UNITED STATES PATENT OFFICE.

H. H. SCOVILLE AND P. W. GATES, OF CHICAGO, ILLINOIS.

IMPROVED APPARATUS FOR AMALGAMATING GOLD AND SILVER.

Specification forming part of Letters Patent No. 44,343, dated September 20, 1864.

To all whom it may concern:

Be it known that we, H. H. SCOVILLE and P. W. GATES, of Chicago, Cook county, State of Illinois, have invented a new and Improved Amalgamator; and we do hereby declare that the following is a full, clear, and exact description thereof, reference being had to the accompanying drawings, making a part of this specification, in which—

Figure 1 is a longitudinal vertical section through the center of our improved machine. Fig. 2 is a vertical cross section through the scroll and its cylinder. Fig. 3 is a top view of our machine. Fig. 4 is a perspective view of the discharge aperture of the scroll.

Similar letters of reference indicate corresponding parts in the several figures.

This invention relates to a new and improved machine for the amalgamation of metals, especially of gold, with a view to the separation of the same from the mineral detritus, as will be hereinafter described.

To enable others skilled in the art to make and use our invention, we will describe its construction and operation.

In the accompanying drawings, A represents a wide-mouth hopper which opens into a cylinder, B, within which revolves a scroll, C, that has a central opening, a, communicating with a chamber, D, as shown clearly in Fig. 1. This chamber D communicates at its upper end with a trough, E, within which revolves a drum, E', having flat wings b arranged around its circumference and set obliquely to its axis. The bottom of the trough E inclines toward the deep chamber D, and the outer end of this trough has a discharge-opening through it, as indicated at c, Fig. 1.

The drum E' and the scroll C are driven by means of pulleys, which are applied to their shafts outside of the frame-work. Gearing or any other convenient contrivance may be employed to drive said drum and scroll.

The scroll-cylinder is made up of two heads bolted on each end of a cylinder, and the scroll which rotates within this cylinder is composed of a number of buckets or curved plates, a a, arranged around a spiral central discharge-aperture, a, which is made through one of the scroll-heads F F in such manner that anything taken into the scroll will be discharged through this aperture into the deep chamber D. This scroll, which we have shown

in the drawings, is constructed with six mouths g g; but we do not confine ourselves to any definite number, as more or less may be used as may be found necessary. The principle of operation will be the same if only one mouth be employed.

In the operation of our invention we propose to employ mercury, melted lead, or anything which may be found best suited to the purpose of separating the gold from the quartz; but in the description of the operation of our invention we will describe the use of mercury as it is most commonly used in the separating process. The scroll will be kept about three-quarters full of mercury and the quartz mixed with gold will be put into the hopper A either in a dry state or mixed with water. As the scroll revolves the mouths g g will successively take a portion of the light substance and carry it down into the body of the scroll, where it will be mixed with the heavier substance (mercury) under considerable pressure, and finally discharged at the center of the scroll through the aperture a and deposited into the chamber D. The lighter substance will immediately rise to the surface of the liquid in chamber D, while the heavier substance will fall to the bottom of this chamber, where it can be removed at pleasure by means of a cock located in the bottom, as indicated at h, Fig. 1. By extending the chamber D below the center of the scroll a reservoir is formed for the gold or amalgam which can be withdrawn as often as necessary without taking the whole of the mercury out. The drum E', at the upper end of the chamber D, together with the trough E, forms a conveyer for carrying the quartz along and separating the particles of mercury which are mixed with it, and, as the outer end of this conveyer is the highest, the mercury works its way back to the chamber D, from whence it enters the scroll-cylinder again through the opening i, and is brought in contact with the gold within said scroll.

As we propose to use melted lead instead of mercury for separating gold or other metals from their matrix, we will state that the lead can be kept at the melting point by applying heat directly to the machine. A series of scrolls may be arranged separately on the same shaft. In that case the discharge for all the scrolls would be a common one.

We do not claim to be the inventors of molten lead or its equivalent for separating gold, &c., in our machine, as the use of lead for this purpose was first suggested to us by Matthew Laflin, of Chicago, Illinois.

Having thus described our invention, what we claim as new, and desire to secure by Letters Patent, is—

1. The employment of a scroll, or its equivalent, in the process of separating metals from their mineral matrix, substantially as described.

2. A scroll (having one or more mouths) ar-

ranged within a cylinder, in combination with a reservoir for receiving the substances discharged from said scroll, substantially as described.

3. The employment of a separator, E E', or its equivalent, in combination with a scroll, substantially as described.

HIRAM H. SCOVILLE.
P. W. GATES.
